C. ARNOLD

SPARK PRODUCING FIGURE WHEELED TOY

Filed Sept. 29, 1927

Inventor:

C. Arnold
by *John H. Arnold*
Attorney

UNITED STATES PATENT OFFICE.

CARL ARNOLD, OF NUREMBERG, GERMANY.

SPARK-PRODUCING FIGURE WHEELED TOY.

Application filed September 29, 1927. Serial No. 222,907.

This invention relates to a toy with a spark-producing mechanism operated by a running wheel and with a toy figure. It has become known to mount on a running wheel or on a trundle hoop a driving mechanism for a figure or for a sound-producer which works when the running wheel is running. According to the invention this driving mechanism is utilized for operating at the same time a spark-producing mechanism, the sparks of which are visible from the outer side through coloured transparent panes and a figure which is sitting on the rotating shaft of the driving mechanism, an up and down and forward and backward movement being communicated to this figure.

A toy according to the invention is illustrated, by way of example, in the accompanying drawing in

Fig. 1 in side elevation, in

Fig. 2 in rear elevation and in

Fig. 3 in top plan view.

On a running wheel *c* a driving mechanism *a* is fixed which comprises a driving shaft *b*. This running wheel *c* with the driving mechanism *a* or with the gear wheels of the same is operated by a driving rod *d* inserted into a sleeve mounted on the driving mechanism *a*. The casing of the driving mechanism *a* stands always perpendicular to the ground owing to the angle at which the driving rod is adjusted. Above the driving mechanism *a* a disk *g* covered with emery is fixed. Cerium stones *h* fixed on oscillatable levers *i* slide on this emery disk *g*. The oscillatable levers *i* are fixed on flaps *k* projecting from a disk *m* which is rotated by the driving shaft *l* of the driving mechanism. By the sliding of the cerium stones on the emery disk brushes sparks are produced which are visible from the outside through coloured transparent panes *n* mounted in the disk *m*. A toy figure *o* is loosely mounted, by means of perforated angular flaps *p*, on the downwardly bent portion of the shaft *b* of the driving mechanism *a*, said portion projecting from the casing. The movement of the toy figure on the shaft is limited by a bar *q* fixed on the driving mechanism *a*. The toy figure *o* has movable arms *r* which carry a plate *s* hav-

ing a slot *t*. With this slot *t* engages the shaft *l* of the driving mechanism so that the figure is maintained in vertical position, by lifting the arms *r* the plate *s* can be disengaged from shaft *l* whereupon, after short rotation to the right, the bar *q* separates from the angular flaps *p* of the toy-figure, so that this toy figure can be removed from the shaft.

The operation of the toy is as follows:—

By pushing the driving rod *d* the running wheel *c* is rotated and at the same time the shaft *b* together with the gear-wheels. The spark producing device is operated, simultaneously and produces sparks which become visible through the transparent panes *n* in disk *m*. By the movement of the bent portion of shaft *b* an up and down and forward and backward movement is communicated to the toy-figure *o* and continued as long as the child pushes the driving-rod. When the driving rod is no longer pushed, the operation stops.

I claim:—

1. A toy consisting of a trundle hoop, comprising in combination with the hoop, a casing, a horizontal shaft journaled in said casing projecting at both ends from said casing carrying said hoop on one end and bent at the other projecting end, a driving mechanism in said casing comprising a vertical driven shaft projecting from the top end of said casing, a spark-producing mechanism above said driving mechanism consisting of a disk fixed on the top end of said casing, of a disk fixed on the projecting end of said vertical shaft, oscillatable levers attached to the lower side of said rotatable disk, a cerium stone at the outer end of each lever resting upon said emery disk, coloured transparent panes in said rotatable disk, a toy-figure on the bent projecting portion of said horizontal shaft, and a driving rod adapted to trundle said hoop and to operate said driving mechanism and said spark-producing mechanism and to impart to said toy-figure on said bent portion of the driving shaft up and down and backward and forward movements.

2. A toy as specified in claim 1, comprising in combination with the casing of the driving mechanism, the driving shaft having

a projecting bent portion and the toy-figure mounted on this bent portion of the shaft, of perforated angular flaps fixed to said toy-figure and pushed over said shaft, a bar fixed 5 to said casing and engaging over one of said flaps for preventing accidental detaching of said toy-figure from said shaft, movable arms

of said toy-figures, a plate fixed on said arms and having a slot pushed over said driving shaft so that, when said driving shaft rotates, said toy-figure remains in the vertical position. ¹⁰

In testimony whereof I affix my signature.
CARL ARNOLD.
